UNITED STATES PATENT OFFICE.

FERDINAND JULES CORVILAIN Y MICHEL, OF BILBAO, SPAIN.

MOUNTING FOR DIAMOND-SET TOOLS.

1,370,662.

Specification of Letters Patent.

Patented Mar. 8, 1921.

Application filed August 20, 1920. Serial No. 404,955.

To all whom it may concern:

Be it known that I, FERDINAND JULES CORVILAIN Y MICHEL, a subject of the King of Belgium, and residing at Bilbao, Spain, 5 have invented a certain new and useful Improvement in Mountings for Diamond-Set Tools, of which the following is a specification.

This invention relates to improvements in 10 tools set with diamonds in a crown piece, such, for example, as that shown and described in U. S. Patent No. 1,030,284, dated June 25, 1912.

In the production of the improved mount 15 the diamond is mounted on one end of a copper wire and electrolytically coated with a deposit of copper. The wire and copper deposit are then turned down to the form of a cylinder merging into a truncated cone 20 in which latter the diamond is embedded and from which the working face of the diamond projects or emerges, so much of the cylindrical portion being cut off as is necessary to effect the required adjustment.

The residual cylindrical portion and conical portion may then be introduced in the 25 socket of the crown piece and will be solidly maintained in place.

In the accompanying drawings Figures 1 to 30 7^a inclusive, illustrate the improved method of production of the mounting and also show the completed mount.

In the drawing Fig. 1 is an elevation and Fig. 1^a a plan showing a wire 1 of soft 35 pure copper of a diameter of about 8 mm. on which wire the diamond is to be mounted.

As shown in Figs. 2 and 2^a, the wire is drilled at 2 to a depth approximately equal to the height of the diamond so as to form 40 the wire with a tubular end, the walls of the tube having a thickness slightly less than 1 mm.

As shown in Fig. 2, a hole 3 is also drilled in the wire near the other end at right angles to the axis of the wire. 45

As shown in Figs. 3 and 3^a, the tubular end is then sawn with an ordinary hack-saw to the depth of the part that has been drilled, leaving four fingers 4. The fingers are heated and allowed to cool so as to render 50 them as pliable as possible.

As shown in Figs. 4 and 4^a, the diamond 5 is then mounted between the four fingers 4, being given the right position with the aid of ordinary pliers, the working face of 55 the diamond being on top.

A hook is now passed through the small hole 3 and the copper wire is dipped in an electrolytic copper bath. Electrolytic copper wire is deposited as shown at 6 in Figs. 5 60 and 5^a. The diamond remains embedded in the copper and is tightly fastened.

The copper wire with copper deposit thereon is then placed on a lathe and the truncated cone 7 or 8 cut down, as shown in 65 Fig. 6 or in Fig. 7, depending on the size of the diamond and the angle desired.

I claim,

The improved method of producing a diamond mounting for a diamond set tool of 70 the type referred to, consisting in mounting the diamond on one end of a copper wire, coating it electrolytically with a deposit of copper, and then turning down the wire and deposit to the required form. 75

In testimony whereof I have signed my name to this specification in the presence of two subscribing witnesses.

FERDINAND JULES CORVILAIN Y MICHEL.
